WALL PLAQUE OR SIMILAR ARTICLE

Dorothy A. Catterlin, King County, Wash.

Application December 10, 1953, Serial No. 28,001

Term of patent 7 years

(Cl. D29—23)

To all whom it may concern:

Be it known that I, Dorothy A. Catterlin, have invented a new, original, and ornamental Design for a Wall Plaque or Similar Article, of which the following is a specification, reference being had to the accompanying drawing, forming a part hereof.

The single figure of the drawing is a plan view of a wall plaque or similar article, illustrating my design. The article is of conventional thickness, and its reverse side is plain.

I claim:

The ornamental design for a wall plaque or similar article, substantially as shown and described.
